UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING MACHINE.

Application filed April 27, 1920, Serial No. 376,951. Renewed January 20, 1922. Serial No. 530,725.

To all whom it may concern:

Be it known that I, JOHN KIEWICZ, a citizen of the United States, residing at Boston, county of Suffolk, State of Massachusetts, have invented an Improvement in Sewing Machines, of which the following description in connection with the accompanying drawing, is a specification, like characters on the drawing representing like

10 parts.

This invention relates to two-threaded buttonhole sewing machines of that type in which the under-thread-handling mechanism is carried by a turret which is rotated at 15 each end of the buttonhole to provide for forming the stitches around the buttonhole ends, and particularly to sewing machines of this type which are provided with means operative at the end of the stitching operation on each buttonhole to pull off from the source of supply a sufficient length of the under thread to ensure the proper formation of the first stitch of the next buttonhole, and in which the tension for the under 20 thread is carried by the rotary turret. The object of the present invention is to provide novel means for relieving the tension on the under thread at the time that said length is pulled off so as to avoid any possibility of 25 the under thread being broken during the pulling-off operation.

In order to give an understanding of my invention, I have illustrated in the drawings a selected embodiment thereof which 30 will now be described, after which the novel features will be pointed out in the appended claims.

Fig. 1 is a side view of a portion of a buttonhole sewing machine having my improvements applied thereto;

Fig. 2 is a front view with the overhanging arm omitted;

Fig. 3 is an underside view of the bed frame showing the turret in section;

Fig. 4 is a front view of the turret with the underthread tension thereon and showing also the means for relieving the tension;

Fig. 5 is a section on the line 5—5, Fig. 4;

Fig. 6 is a plan view of a portion of the clamp-plate and bed frame showing the under-thread pull-off and cutter;

Fig. 7 is a view similar to Fig. 6 showing the clamp-plate and cutter removed;

Fig. 8 is a fragmentary view showing the 55 manner in which the pull-off operates.

I have herein shown my invention as it might be embodied in a buttonhole sewing machine of the well-known "Reece" type, exemplifications of which are found in 60 United States Patent No. 1,188,942, June 27, 1916, and No. 1,406,742, February 14th, 1922.

In the drawings, 1 indicates the bed frame of a buttonhole sewing machine of the above-mentioned type which is provided with ways 2 in which the work-holding means is slidably mounted, the latter comprising a clamp-plate 3 and work-clamps 4 pivoted thereto. The bed-plate 1 has the usual arm or head 5 rising therefrom which supports a reciprocating needle-bar 6 carrying the needle 7 that controls the upper thread 8. The under-thread 9 is manipulated by an under-thread mechanism carried by a turret 10 which is rotatably mounted in the depending portion 11 of the frame, all as usual in sewing machines of this type.

This under-thread mechanism is of the type usually employed in sewing machines 80 of this character, and it comprises an oscillating under needle 12 which operates through the usual throat-plate 13 carried by the turret, a looper 14 which is actuated to take the loop of upper thread and hold 85 it while the under needle 12 inserts the under thread through said loop, and a tension device 15 carried by the turret through which the under thread passes on its way to the 90 needle.

The turret carries the usual hollow spindle 16 through which the under thread 9 passes on its travel to the tension 15 and which is vertically movable to actuate the under thread mechanism. This spindle is 95 provided with a slot 17 through which the thread is led to a guide-eye 18 from which it passes to the tension. The tension is of the usual type comprising two friction disks 20 between which the thread is led, and one 100 of which is acted on by a spring 21 to provide the desired friction.

The machine herein shown is also provided with means operating on the under thread between the throat-plate 13 and the needle 12 for pulling off a length of thread from the source of supply to the tension 15 at the end of each buttonhole, thereby pro-

viding a sufficient length of thread to ensure the proper formation of the first stitch on the next buttonhole.

The pull-off device herein shown is similar to that illustrated in Patent No. 1,406,742, and it comprises a pull-off lever 22 pivoted at 23 to the bed plate and formed at its end with a hook 24 adapted to engage the under thread and by a backward pulling movement thereon to draw off a length from the source of supply. The pull-off lever 22 is normally held in the full line position, Fig. 7, by a spring 25, and at the end of the stitching operation on a buttonhole, the outer end thereof is acted upon by an actuating lever 26 which is pivoted to the bed frame at 34 and which operates to swing the pull-off lever into the dotted line position, Fig. 7, thereby carrying the hooked end thereof beneath the throat-plate and into position so that the under thread 9 will drop behind the hook. When the pull-off lever has been moved into this position it is released and the spring 25 returns it to the full line position, thus causing the hook to form a bight in the under thread 9 between the throat-plate and the under needle 12 thereby pulling a length of under thread from the source of supply. The swinging of the pull-off lever into the full line position carries the hook beneath a clamping plate 27 so that the thread is clamped between the hook and the clamping plate. After a length of under thread has been pulled off and clamped, the under thread is trimmed close to the work and between the latter and the throat-plate by a trimming knife 28 which is pivoted to the clamp plate 3 at 29, and which is provided with a shearing edge 30 that co-operates with the shearing block 31 to sever the under thread. This cutting knife is normally held in full line position by a spring 61, and it is given its cutting movement by the lever 26. The construction is such that the initial movement of the actuating lever 26 operates the pull-off lever 22 and then releases it, while the final movement of said actuating lever then operates the cutter 28. During the initial movement of the lever 26 from its full line position Fig. 7 to just beyond the dotted line position *a*, the end of said lever wipes by the end of the pull-off lever and actuates the latter, and then releases it, and at this time a projection 32 on said actuating lever 26 is brought against a shoulder 33 on the cutter so that further movement of the lever operates the cutter. This mechanism for actuating the cutter and the pull-off is shown and described more in detail in Patent No. 1,406,742.

The lever 26 is actuated at the proper time by means of a roller 35 carried by an arm 36 which is rigid with the usual feed

cam 39 by which the work-holding means is given its feeding movement.

When the pull-off lever 22 operates to draw off a length of under thread, such length is pulled off through the tension 15, and if the thread is of a poor quality, or if the tension is considerable, there is a possibility that the thread may become broken. To obviate this, I have provided a novel means for relieving the tension on the under thread at the time that the pull-off lever actuates, and I propose to accomplish this herein by a tension-releasing device which is actuated by the lever 26. Pivoted on the turret is a tension-releasing member 37, said member being pivoted to the turret at 38 and having at its upper edge a wedge-shaped portion which is adapted to be forced between the tension disks 20 thereby to separate them. This tension-releasing member 37 is acted on by a spring 58 which normally tends to hold it in inoperative position with a projection 40 thereon resting against the inside of the portion 41 of the turret. This is the position of the tension-releasing member during the stitching on a buttonhole. When the buttonhole is completed and the parts are in position for the pull-off to operate, the turret will be turned into the position shown in Fig. 2 with the tension on the back side thereof.

The depending portion 11 of the frame has a lever 42 pivoted thereto at 43, one arm 44 of said lever having a cam surface 45 on its under side which is acted upon by the lever 26 as the latter is given its actuating movement. The other end 46 of said lever is in position to engage the upper end of the tension-releasing member 37. The end 46 of said lever is shaped so that when the turret arrives at the position shown in Figs. 2 and 4 at the end of the stitching operation, the tension-releasing member 37 will be situated opposite said end 46 and, therefore, if the arm 44 of said lever is raised, the end 46 will engage the tension-releasing member and swing it to the left Fig. 4, thus separating the tension disks and relieving the tension on the under thread. The parts are so constructed that during the actuating movement of the lever 26, it engages the cam surface 45 of the lever 42, thus causing said lever to actuate the tension-releasing member 37, and the tension is thus released while the under thread is being pulled off. As a result, the under thread is free from tension while it is being pulled off and there is no danger of its becoming broken due to a heavy tension thereon.

I claim:

1. In a two-thread sewing machine of the type adapted to sew a short seam and then come to rest, the combination with a frame, of work-holding means carried thereby,

means to give a feeding movement to the work-holding means, a rotary turret mounted in the frame and carrying the under-thread mechanism, a tension for the under-thread carried by the turret, means to pull off a length of under thread through the tension at the end of each sewing operation, and means actuated thereby to release the tension on the under thread while such 10 length is being pulled off.

5. In a two-thread sewing machine of the type adapted to sew a short seam and then come to rest, the combination with a frame, of a rotary turret carrying the under-thread 15 mechanism, a tension for the under thread carried by the turret, a pull-off device to pull off a length of under thread through the tension at the end of each sewing operation, an actuating lever for actuating said pull-off device, and means actuated thereby to release the tension for the under thread.

20 3. In a two-thread sewing machine of the type adapted to sew a short seam and then come to rest, the combination with a frame, of work-holding means movably carried thereby a rotary turret carrying the under thread mechanism, a tension for the under thread carried by the turret, a pull-off lever pivoted to the frame for pulling off a length 25 of under thread through the tension at the end of each sewing operation, a tension-releasing member, and means common to said pull-off lever and tension-releasing member to actuate them both.

30 4. In a two-thread sewing machine of the type adapted to sew a short seam and then come to rest, the combination with a frame, of a rotary turret carrying the under thread mechanism, a tension for the under thread 35 carried by the turret, a pull-off lever for pulling off a length of under thread through the tension at the end of each sewing operation, a tension-releasing member, an actuat-

ing lever pivoted to the frame and constructed to operate both the pull-off lever and the 45 tension-releasing member.

5. In a two-thread sewing machine, the combination with a frame, of a rotary turret mounted therein and carrying under-thread mechanism, a tension for the under-thread also carried by the turret, a tension-releasing member pivoted to the turret, a lever pivoted to the frame, a second lever actuated thereby and adapted to engage the tension-releasing member to release the tension for the under thread.

6. In a sewing machine, the combination with a frame, of work-holding means carried thereby, a feed cam for giving feeding movement to said work-holding means, a rotary turret carrying under-thread mechanism, a tension for the under thread carried by the turret, a lever pivoted to the frame, means associated with said feed cam for actuating the lever, and means actuated by the 60 lever to release the tension and pull off a length of under thread.

7. In a two-thread sewing machine of the type adapted to sew a short seam and then come to rest, the combination with a frame, 70 of work-holding means carried thereby, stitch-forming mechanism including a rotary turret mounted in the frame and carrying the under-thread mechanism, means for giving the work-holding means and stitch-forming mechanism a relative movement, a tension for the under thread carried by the turret, means separate from the first-named means to pull off a length of under thread through the tension at the end of each sewing 75 operation and means actuated thereby to release the tension on the under thread while such length is being pulled off.

In testimony whereof, I have signed my name to this specification.

JOHN KIEWICZ.
